VACUUM SWEEPER

Carl O. Bergstrom, Boston, Mass., assignor to
 B. F. Sturtevant Company, Inc., Hyde Park,
 Boston, Mass.

Application February 26, 1935, Serial No. 8,290

4 Claims. (Cl. 15—8)

This invention relates to vacuum sweepers of the type employing rotary, sweeping brushes.

The ordinary electric motor which drives the rotary mechanism in a vacuum sweeper of the household type is necessarily operated at a high armature speed of approximately 3,000 revolutions per minute, in order that the blower produce sufficient suction. Such high motor speeds have opposed the successful operation of power driven sweeping brushes as auxiliaries to vacuum sweepers. It is desired to drive both the blower and the sweeper brush of a vacuum sweeper with the same motor, but when the member carrying the sweeper brushes is rotated at speeds approximating those of the motor armature, the action of the brushes is more a polishing action, than a sweeping one.

It is desirable that the rotary speed of the sweeping member of a vacuum sweeper be reduced substantially below that of the sweeping motor. A speed reduction such that the sweeping member revolves at about 800 revolutions per minute has been found satisfactory. Attempts to obtain this reduction in speed have been made in the past, through the use of gear trains, planetary transmissions, etc., but the space available for this additional mechanism is so limited and the noise of, and the power losses in, operation of such mechanisms have prevented their successful operation.

According to this invention, the speed reducing mechanism for driving the sweeper brushes of a vacuum sweeper is confined within a brush carrying cylinder of small diameter.

According to a feature of this invention, a pair of ball bearings is used to accomplish the desired speed reduction. A brush carrying cylinder is divided at its longitudinal center into two independent portions, each carrying a plurality of the usual sweeper brushes. A common shaft extends through both cylinders and attached to this shaft between the two cylinders is a pulley adapted to be rotated by a belt from another pulley carried by the shaft of the blower driving motor. To each outer end of the shaft extending through the two brush carrying cylinders is attached the inner race of a ball bearing. The outer races of these two ball bearings are held against rotation by the vacuum sweeper housing. The ball retaining ring in each bearing is attached to the outer end of its respective brush carrying cylinders.

In operation, the shaft extending through the two is rotated by the action of the blower motor. This shaft rotates the inner races of the two ball bearings. The balls are rotated between their inner and outer races and since the outer races are held against rotation, the balls, in their rotation, revolve the ball retaining rings at a substantially lower speed, the reduction in speed de-

pending primarily upon the size of the balls. Since the ball retaining rings are attached to the two brush carrying cylinders, it is seen that the cylinders are rotated at the same reduced speed.

Since the speed reduction is accomplished through the use of a pair of simple balls or other type of roller bearings, not only is ample space for their inclusion available but what is also important, the noise of operation is slight and the efficiency is high, all of these factors resulting in the production for the first time, of a small compact unit, which not only is effective in its sweeping operation, but is inexpensive, quiet in operation and consumes but relatively little power.

An object of the invention is to drive a relatively low speed sweeper in a household vacuum sweeper from a relatively high speed blower motor, in quiet and efficient operation.

Another object of the invention is to provide a quiet compact vacuum sweeper with revolving sweeper brush rotated at relatively low speed.

Another object of the invention is to drive a relatively low speed sweeper brush in a household vacuum sweeper, from a relatively high speed blower motor by driving the inner race of a ball or roller bearing by the motor, holding the outer race against rotation and attaching the sweeper brush to the ball or roller retaining ring of the bearing.

Other objects of the invention will be apparent from the following description taken together with the drawing.

The invention will now be described with reference to the drawing, of which:

Fig. 1 is a partial view, partially in section, illustrating the sweeper brush driving mechanism of a household vacuum sweeper, according to this invention;

Fig. 2 is a sectional view, along the lines 2—2 of Fig. 1, and

Fig. 3 is a sectional view along the lines 3—3 of Fig. 2.

The two duplicate sweeper cylinders 4 are rotatably attached at their outer ends, by means of the clamping members 5 to the sweeper housing 6 and are so placed above the suction opening in the sweeper that when they are rotated, their brushes exert the desired sweeping action upon the surface being cleaned. The cylinders 4 are simultaneously rotated by the motor 7 which ordinarily drives the blower 8, by means of the belt 9 which extends over the pulley 10 on the motor shaft and the pulley 11. The pulley 11 is attached to the shaft 12 which extends through a central opening in both cylinders 4.

At each end of the shaft 12 are, fixedly attached, the hub member 13, on which is shrunk, forced or otherwise suitably attached, the inner race 14 of a ball or roller bearing which revolves with the shaft 12. Between the balls 15 of the

bearing, the pins 16 are attached at one end to the retaining ring 17. The other ends of the pins 16 are attached to the member 18, which in turn is attached to the outer race 19 of a relatively small ball bearing mounted within each cylinder 4, and to the cylinder as by a forced or shrunk fit so that rotation of each retaining ring 17 causes, through the intermediary of the pins 16 and member 18, rotation of the cylinder.

10 The inner race of the relatively small ball bearing, above mentioned, rests upon the shaft 12, the purpose of this relatively small bearing being merely to support the outer end of its respective cylinder 4 upon, and to facilitate its rotation around the shaft.

15 The outer race 20 of each relatively large bearing is held to prevent its rotation by pressure of the clamping members 5 against it. The clamping members 5 are attached to the housing 6 of the vacuum sweeper by means of the screws 21. An inwardly extending portion 22 of each member 5 is grooved to receive the felt 23, the outer portion of which is pressed against the outer surface of each cylinder to prevent the entry of 25 dust into the outer bearings.

20 The inner end of each cylinder 4 is supported through the intermediary of the member 24 upon the outer race of a relatively small bearing indicated generally by 25 and the inner race of 30 which rests upon the shaft 12, the purpose of this bearing being merely to support the inner end of the cylinder and to facilitate its rotation around the shaft 12 which as will be explained later, rotates at a different speed.

35 With the armature of the motor 7 in rotation, the belt 9 is driven by the pulley 10 to rotate the pulley 11 which in turn rotates the shaft 12 which extends through the two cylinders 4. The shaft in rotation rotates the hub member 13 and 40 the inner ball race 14 due to the fact that the outer ball race 20 is held by the clamping member 5 to prevent its rotation. The retaining ring 17 rotates around the inner ball race 14 at a reduced speed. This rotation of the retaining rings 45 causes the rotation of the cylinders 4 through the intermediary of the pins 16 and members 18 in which the pins are held at one end.

50 The cylinders 4 are rotated simultaneously in the same direction as described above and during rotation, the plurality of brushes 26 sweep the surface which is being cleaned.

55 The cylinders 4 rotate with little effort other than that required to force the brushes 26 across the surface being cleaned since they are supported and rotated on the shaft 12 by the relatively small ball bearings mounted in each end of both cylinders. The speed reduction is obtained through the two relatively large ball bearings mounted at the outer ends of the cylinders and 60 the outer races of which are held against rotation. These bearings are adapted to be lubricated in the usual manner. Since the speed reduction is obtained through the use of the ball bearings, power losses are very small and the noise of 65 operation negligible. Then again, as pointed out above, it is possible to place the entire mechanism within a very small space as illustrated.

70 In the foregoing description, reference has been made to ball bearings. The invention, however, is not so limited since any equivalent form of bearings, such as cylindrical roller bearings, may be used. The term "roller bearings" as used

herein, is intended to include these and equivalent types.

Whereas, one embodiment of the invention has been described for the purpose of illustration, it should be understood that the invention is not limited to the exact arrangement described, since many departures will suggest themselves to those skilled in the art, after having had access to this disclosure.

What is claimed is:

1. In a vacuum cleaner, an agitator comprising a cylinder having agitating elements on the periphery thereof, a rotatable shaft supporting said agitator, a motor, means for driving said shaft by said motor, a speed reducing mechanism of the roller bearing type having an inner race mounted on said shaft for rotation therewith, an outer race and a roller retaining ring, means for holding said outer race against rotation whereby on rotation of said inner race by 20 said shaft, said ring is rotated at a reduced speed, and means connecting said ring and said cylinder whereby said cylinder is rotated by said ring.

2. In a vacuum cleaner, an agitator comprising a cylinder having agitating elements on the periphery thereof, a rotatable shaft supporting said agitator, a motor, means for driving said shaft at one end of said cylinder by said motor, a speed reducing mechanism of the roller bearing type having an inner race mounted on said shaft at 30 the other end of said cylinder for rotation therewith, an outer race and a roller retaining ring, means for holding said outer race against rotation whereby on rotation of said inner race by said shaft, said ring is rotated at a reduced speed, and means connecting said ring and said cylinder whereby said cylinder is rotated by said ring.

3. In a vacuum cleaner, an agitator comprising a pair of cylinders having agitating elements on the peripheries thereof, a rotatable shaft supporting said agitator, a motor, means for driving said shaft by said motor, the connection between said means and the shaft being located between the cylinders, a speed reducing mechanism of the roller bearing type having an inner race for each cylinder mounted on said shaft for rotation therewith, an outer race and a roller retaining ring for each cylinder, means for holding said outer races against rotation whereby on rotation of said inner races by said shaft, said rings are rotated at a reduced speed, and means connecting each of said rings with its respective cylinder whereby said cylinders are rotated by said rings.

4. In a vacuum cleaner, an agitator comprising a pair of cylinders having agitating elements on the peripheries thereof, a rotatable shaft supporting said agitator, and extending through said cylinders, a pulley attached to said shaft between said cylinders, a motor, means for rotating said pulley from said motor, a speed reducing mechanism of the roller bearing type having an inner race for each cylinder mounted on each end of said shaft for rotation therewith, an outer race and a roller retaining ring for each cylinder, means for holding said outer races against rotation whereby upon rotation of said inner races by said shaft, said rings are rotated at a reduced speed, and means connecting each of said rings with its respective cylinder whereby said cylinders are rotated by said rings.
